Des. 187,745
Patented Apr. 26, 1960

187,745

MATERIAL HANDLING POLE

Frank E. Bird, Jr., Coatesville, Pa.

Application July 14, 1959, Serial No. 56,776

Term of patent 14 years

(Cl. D41—1)

FIG. 2.

FIG. 3.

FIG. 1.

Fig. 1 is a side elevational view of a material handling pole embodying my new design, the handle being broken away for convenience of illustration only;

Fig. 2 is a top plan view thereof; and

Fig. 3 is a side perspective view thereof, the opposite side being substantially the same as the side shown.

I claim:

The ornamental design for a material handling pole, as shown and described.
